UNITED STATES PATENT OFFICE.

FRANK L. KOEPEKE, OF WHITEHALL, WISCONSIN.

LEADING AND SUBDUCING BRIDLE.

1,209,724.

Specification of Letters Patent. Patented Dec. 26, 1916.

Application filed March 31, 1916. Serial No. 88,080.

To all whom it may concern:

Be it known that I, FRANK L. KOEPEKE, a citizen of the United States, residing at Whitehall, in the county of Trempealeau, 5 State of Wisconsin, have invented certain new and useful Improvements in Leading and Subduing Bridles; and I do hereby declare the following to be a full, clear, and exact description of the invention, such as 10 will enable others skilled in the art to which it appertains to make and use the same.

This invention relates to improvements in leading and subduing bridles for unruly animals.

15 One object of the invention is to provide a novel and simple device of this character which will automatically tighten should the animal resist or pull away, but which will immediately and easily assume a normal and 20 comfortable position to the animal when the animal ceases to struggle.

Another object is to provide a device of this character which is so constructed that it can be quickly and easily adjusted to fit any 25 animal, and which will at all times operate in an efficient manner no matter from what direction the leading rope is pulled.

Other objects and advantages will be apparent from the following description when 30 taken in connection with the accompanying drawing.

In the drawing: Figure 1 is a side elevation of my improved leading bridle or halter shown applied to a horse's head; Fig. 2 is an 35 enlarged perspective view of the device removed from the animal's head, the animal's head being dotted in.

Referring particularly to the accompanying drawing, 10 represents a bit member 40 which may be formed of any suitable material, such as a bar of metal, plaited or twisted rope or the like, and movably mounted on one end of this bit member is a ring 11 through which is engaged a portion of the 45 rope 12 which is adapted to pass up over the animal's head. On the end of this rope, above the ring 11 is a smaller ring 13. The other portion of the rope 12 passes through the ring 13, and has engaged thereon a ring 50 14 which forms a loop 15 of the portion of the rope which passes through the ring 13.

Thus the rings 13 and 14 form a clutch lock whereby the rope 12 can be slipped through the ring 13 so as to adjust the rope for different sized animals. On the other end of the 55 rope 12 is mounted a block 16 in which is rotatably supported a pulley 17. Movable mounted on the other end of the bit member are two rings 18 and 19, the former of which has thereon a block 20 in which is mounted 60 a pulley 21. Secured to the ring 11, and engaged around the rear of the horse's head is a rope 22, the same being passed through the block 20, then through the block 16, and down through the ring 19. It will thus be 65 seen that upon pulling downwardly on the portion of the rope below the ring 19, said rope will be moved through the pulley blocks so as to draw upwardly on both ends of the bit member, and at the same time draw the 70 loop at the rear of the animal's head into a taut condition, so as to exert pressure against the back of the head.

In similar devices heretofore, the rope 22 was passed through the ring corresponding 75 to the ring 18, but when a pull on the rope 22 was exerted from the front or toward the rear of the animal, this ring was twisted so as to move the pulley 21 out of proper alignment, and with the consequent jamming 80 or tangling of the parts. The particular object in providing the extra ring 19 and passing the rope 22 therethrough, instead of through the ring 18, effectively prevents any 85 twisting of the ring no matter from what direction the rope is pulled. Attention is also particularly directed to the adjustment by means of the rings 13 and 14. The ring 14 serves as an effective lock so as to wedge the 90 rope 12 into firm engagement with the ring 13, and thus prevents the rope slipping after having once been adjusted.

What is claimed is:

A leading and subduing bridle, comprising a halter including a bit member, a ring 95 movably connected to one end of the bit, a pair of rings movably connected to the other end thereof, a cord engaged through the single ring and passed over the animal's head, a pulley carried by the end of the cord, adjusting means carried by the other end of the 100 cord and engaging therewith, intermediate

the ends thereof, a pulley carried by one of the said pair of rings, and a cord secured to the first-named ring and engaging both of the pulleys and passing through the other of 5 the pair of rings and adapted to pass over the neck of the animal.

In testimony whereof, I affix my signature, in the presence of two witnesses.

FRANK L. KOEPKE.
